CYLINDER SUPPORT FOR CIRCULAR RIB KNITTING MACHINES

Original Filed May 28, 1932

UNITED STATES PATENT OFFICE

1,988,359

CYLINDER SUPPORT FOR CIRCULAR RIB
KNITTING MACHINESWalter Larkin, Norristown, Pa., assignor to
Fidelity Machine Company, Wilmington, Del.,
a corporation of DelawareOriginal application May 28, 1932, Serial No.
614,216. Divided and this application January
6, 1933, Serial No. 650,541

3 Claims. (Cl. 66—19)

The invention hereinafter disclosed relates primarily to means for axially shifting the needle cylinder of a circular knitting machine, and more particularly to means for shifting the needle cylinder of a rib knitting machine relative to the needle dial of the machine, whereby the needle dial, in turn, may be shifted axially into cooperative relation to the needle cylinder at a predetermined position with respect to a double thread 10 guide and other instrumentalities which occupy relatively fixed positions and cooperate with the cylinder and dial needles, whereby said instrumentalities will engage but one of two threads respectively and simultaneously fed to the 15 needles by the double thread guide, for purposes fully disclosed in the applicant's copending application, Serial No. 614,216, filed May 28, 1932, of which the present application is a division.

As the invention disclosed in the present application concerns only the means by which shifting of the needle cylinder is effected the following description will be confined to the mechanism by which the needle cylinder is normally supported, for ordinary knitting, and the 20 means by which the needle cylinder may be adjusted axially into said normal knitting position or shifted from said normal knitting position to the predetermined position above referred to, for special knitting, as disclosed in the above 25 noted parent application.

The single figure of the accompanying drawing is a vertical sectional elevation taken through the needle cylinder and its supporting and adjusting means and discloses sufficient of the machine involved for illustrating the construction 30 of the mechanism forming the subject matter of the present invention and the cooperation of such mechanism with the other elements of the machine for attaining the desired result.

The machine comprises a base plate 1 to which is secured a hollow annular element 2, by means of screws 3, 3. The hollow annular element 2 is 35 provided with a horizontally extending internal flange 4, to the upper side of which is secured, by means of screws 5, a base ring 6.

The base ring 6 is provided with an inwardly projecting horizontal flange 7 to the underside of which is secured, by means of screws 8, a readily removable cylinder carrying or support- 40 ing ring 9.

The cylinder-carrying ring 9 is circularly recessed at 10 to receive the lower end of a needle cylinder 11, said cylinder being axially aligned with the ring 9 by means of a vertical annular 45 wall 12 formed in the ring 9 by the said recessing

thereof, said wall functioning to center and guide the cylinder 11 during relative axial movement thereof with respect to the ring 9, when said cylinder is shifted axially in the machine.

In the base of the recess or shallow bore 10 of the supporting ring 9 is formed a counterbore 13 in the base of which is formed a centrally disposed threaded opening or bore 14 which extends completely through the ring 9.

The counterbore 13 of the ring 9 is adapted to 10 receive an annular flange 15 formed on the upper end of a cylinder-adjusting ring 16. The cylinder-adjusting ring 16 is provided with threads 17 which cooperate with corresponding threads formed in the through bore 14 of the 15 supporting ring 9, to effect vertical movement of the cylinder-adjusting ring 16 relative to the stationary carrying ring 9, upon rotation of the ring 16 within the ring 9. The cylinder-adjusting ring 16 is provided with depending lugs 19, 20 affording means by which the ring 16 may be 25 rotated with respect to the ring 9.

The lower end surface 11a of the needle cylinder 11 bears on the upper surface of the flange 15 of the cylinder-adjusting ring 16, and is adapted to be clamped tightly against the upper surface of the flange 15 by means of screws 20, 20 which pass through suitable apertures formed in the carrying ring 9 and are threaded, at their upper ends, into tapped openings 21 30 formed in the lower end of the cylinder 11.

By loosening the screws 20, 20 and by rotating the cylinder-adjusting ring 16 within the cylinder-carrying ring 9 axial shifting of the cylinder 11 may be readily effected. After the predetermined position of the cylinder 11 is obtained the cylinder may be secured in said position merely by tightening the screws 20, 20 which, by clamping the cylinder 11 tightly against the adjusting ring 16, prevents accidental rotation of the ring 16 in the ring 9, whereby the predetermined position of the cylinder 11 is maintained indefinitely.

If desired, the cylinder 11 may be entirely removed from the machine by removing the 45 screws 8, 8 which secure the carrying ring 9 in position in the machine, after which the carrying ring 9, the adjusting ring 16 and the cylinder 11 may be dropped through the base ring 6 and hollow annular support 2.

The peripheral surface of the flange 15 on the adjusting ring 16 has a snug fitting bearing in and against the circular peripheral wall of the counterbore 13 in the cylinder carrying ring 9 which at all times keeps the upper cylinder- 55

supporting surface 18 of the ring 16 level, by preventing tilting of the ring 16 in event of there being any looseness between the threads 17 of the ring 16 and the threads 14 of the ring 9. Such looseness, when the screws 20 are tightened to secure the cylinder 11 in place, would cause the ring 16 and the cylinder 11 to tilt and thereby throw the axes of the ring 16 and the cylinder 11 out of alignment with each other and with the cooperating parts of the machine which revolve about the axis of the cylinder 11 and which would cause binding of such parts against the cylinder 11, causing excessive wear therebetween. The flange 15 by having a snug fitting bearing in the counterbore 13 obviates such conditions.

I claim:

1. The combination of a circular knitting machine of a base plate, a cylinder-supporting ring removably secured to the base plate, a cylinder secured to said supporting ring, an adjusting ring threaded into said supporting ring and engaging said cylinder for shifting the cylinder axially with respect to said supporting ring, a flange on said adjusting ring provided with a peripheral cylindrical wall concentric to the axis of the adjusting ring and having a snug fitting bearing in a counterbore formed in said cylinder supporting ring, said adjusting ring having a cylinder supporting surface perpendicular to the axis of said adjusting ring, and means for rigidly clamping said rings and said cylinder together as a unit.

2. The combination of a circular knitting machine of a base plate, a cylinder-supporting ring removably secured to the base plate, a cylinder secured to said supporting ring, an adjusting ring threaded into said supporting ring and engaging said cylinder for shifting the cylinder

axially with respect to said supporting ring, a flange on said adjusting ring provided with a peripheral cylindrical wall concentric to the axis of the adjusting ring and having a snug fitting bearing in a counterbore formed in said cylinder supporting ring, said adjusting ring having a cylinder supporting surface perpendicular to the axis of said adjusting ring, and screws passing through said supporting ring and tapped into said cylinder externally of and spaced circumferentially about said adjusting ring for securing said rings and said cylinder together as a unit.

3. The combination of a circular knitting machine of a base plate, a cylinder-supporting member removably secured to the base plate, a cylinder member secured to said supporting member, a rotary adjusting element intermediate and axially aligned with said cylinder and supporting members and having spiral threaded engagement with at least one of said members for shifting the cylinder member axially with respect to the supporting member, means formed on one of said members and extending parallel to the axis of and in circumambient relation to the other of said members to prevent lateral movement between said members during relative axial shifting therebetween, a flange on said rotary adjusting element having a cylindrical peripheral wall concentric to the axis of said element and having a snug fitting bearing in a circular concentric counterbore formed in the member with which said element has said threaded engagement, said adjusting element having a bearing surface perpendicular to the axis thereof for engagement with the other of said members, and means for clamping said members and said intermediate element in substantially fixed relation to each other.

WALTER LARKIN.
